(57) **CLAIM**

The ornamental design for a pet bag, as shown and described.

DESCRIPTION

FIG. 1 is a perspective view of a pet bag showing my new design with the window in an open position;

FIG. 2 is an alternate perspective view of the pet bag showing the top cover in an open state, the window in a closed position, and the handles set on the sides;

FIG. 3 is a front elevational view thereof, showing the design in an alternate position, with the top cover and the window in closed state and the handles set on the top side;

FIG. 4 is an alternate front elevational view thereof; showing the window in an open state;

FIG. 5 is a left side elevational view thereof; showing the window and the top cover in closed state;

FIG. 6 is a right side elevational view thereof,

FIG. 7 is a top plan view thereof; and,

FIG. 8 is a bottom plan view thereof.

The dash-dot-dash lines depict portions of the pet bag that form no part of the claimed design. The zipper sliders shown in short dashed broken lines depict portions that form no part of the claimed design. The short dashed broken lines disclose stitching which forms part of the claimed design.
